(57) **CLAIM**

The ornamental design for a holder accessory for a mobile device as shown and described.

DESCRIPTION

FIG. 1 is a perspective view of a holder accessory for a mobile device showing our new design;

FIG. 2 is a front side view thereof, wherein the back, left, and right side views are identical to the front side view;

FIG. 3 is a top view thereof;

FIG. 4 is a bottom view thereof;

FIG. 5 is a front side view thereof in an alternate position, wherein the back, left, and right side views are identical to the front side view in the alternate position; and,

FIG. 6 is a perspective view thereof in an alternate position.

1 Claim, 6 Drawing Sheets
